UNITED STATES PATENT OFFICE.

THOMAS G. RICHARDS, OF BROOKFIELD, MASSACHUSETTS, ASSIGNOR TO QUABAUG RUBBER COMPANY, OF BROOKFIELD, MASSACHUSETTS, A CORPORATION OF MASSACHUSETTS.

DESIGN FOR A RUBBER MAT.

58,941.

Specification for Design. Patented Sept. 6, 1921.

Application filed October 23, 1919. Serial No. 332,839. Term of patent 14 years.

To all whom it may concern:

Be it known that I, THOMAS G. RICHARDS, a citizen of the United States, residing at Brookfield, in the county of Worcester and State of Massachusetts, have invented a new, original, and ornamental Design for Rubber Mats, of which the following is a specification, reference being had to the accompanying drawing, forming part thereof.

In the drawing Figure 1 is a plan view of a rubber mat showing my new design, and Fig. 2 is a detail section on line 2—2 of Fig. 1.

I claim: —

The ornamental design for a rubber mat, as shown.

THOMAS G. RICHARDS.
